PEN HOLDER

Bluford M. Mason, Houston, Tex.

Application January 10, 1955, Serial No. 33,908

Term of patent 14 years

(Cl. D74—1(6))

To all whom it may concern:

Be it known that I, Bluford M. Mason, a citizen of the United States, residing at Houston, in the county of Harris, in the State of Texas, have invented a new, original, and ornamental Design for a Pen Holder, of which the following is a specification, reference being had to the accompanying drawing, forming a part thereof.

The pen shown in dotted lines in Figure 1 and partly shown in Figure 2 is for illustrative purposes only.

I claim:

The ornamental design for a pen holder, as shown and described.
